UNITED STATES PATENT OFFICE

2,577,471

SPROCKET AND ROLLER COMBINATION
FOR TRUSSSED TRACKS

Harry Y. Law, Merced, Calif.

Original application June 7, 1943, Serial No. 489,910, now Patent No. 2,426,032, dated August 19, 1947. Divided and this application June 9, 1947, Serial No. 753,537

4 Claims. (Cl. 305—8)

1

This application is a division of the subject matter shown in my pending application, Serial No. 489,910, filed June 7, 1943, now Patent No. 2,426,032, dated August 19, 1947, being directed to subject matter shown and described but not claimed in said application.

The object of the invention claimed in this divisional application is to provide in a trussed track construction of the type described in said application, a novel sprocket and roller combination in which the relative sizes and positioning of the track driving sprockets and the track supporting or idler rollers is such that one roller contacts both the upper and lower track rail surfaces adjacent the corresponding sprocket; also to provide a structure in which the size of the sprocket relative to the pitch length of the links is such that the horizontal distance between the axis of each roller and that of the adjacent sprocket will be equal to the length of a link without the periphery of the roller intersecting the axis of the sprocket, thus placing the links in position for the rollers to pass over them without knocking.

These objects are accomplished by means of such structure and relative arrangement of parts as will fully appear by a perusal of the following specification and claims.

In the drawings:

Figure 1 is a side elevation of one form of my improved endless track unit.

Figure 2 is an enlarged fragmentary elevation, partly in section, of the track linkage detached.

Figure 3 is a plan view of a pair of connected links.

Figure 4 is a fragmentary transverse section on the line 4—4 of Fig. 1.

Figure 5 is a fragmentary side elevation of a modified form of track unit.

Referring now more particularly to the characters of reference on the drawings, and particularly at present to Figs. 1 to 4, the track links, which are the essential features of the invention, each comprise a shoe 1 having a transverse cleat 2 on one end. A central pin boss 3 is formed with and inwardly from the shoe at said one end, and transversely spaced bosses 4 are disposed in a similar position on the opposite end of the shoe to receive the boss 3 of an adjacent link therebetween. Link pins 5 swivelly connect corresponding bosses.

Longitudinally extending webbing 6, disposed in a plane at right angles to the shoe, extends between and connects the bosses inwardly thereof. The webbing at the boss 3 is in the form of

2

a central web element 7, while at the opposite end it is in the form of transversely spaced or forked elements 8. The webbing terminates in a flat longitudinal surface 9 which forms a roller engaging rail parallel to the shoe, and the major portion of which is the same width as the boss 3. Over said boss, however, the surface is in the form of a central tongue 10 narrower than said boss, said tongue terminating in abrupt shoulders 11 at the junction with the wider portion of the surface. Beyond the shoulders said surface 9 is forked to provide a slot 12 therebetween to receive the tongue of an adjacent link; the width of this slot being the same as the spacing between the web elements 8. A transverse pin 13 is secured in the web element 7 adjacent the outer end of the tongue and projects laterally beyond opposite sides thereof; while a similarly disposed pin 14 is secured in the web elements 8 and extends across the slot 12. Both pins lie in a plane parallel to the link pin centers inwardly thereof but outwardly of the rail 9, as clearly shown in Fig. 2, and are considerably farther apart than the bosses and link pins, but symmetrically positioned relative thereto. The bosses 15 in which the pins 13 and 14 are mounted are the same width as the corresponding portions of the track 9 and merge into the same with a curve, as shown. Formed along the outer edge of the webbing 6 under the track and between the bosses 3 and 4 are saddles 16 and 17 to receive the pins 13 and 14, respectively, of adjacent links, and facing the shoe. These saddles are positioned to seat the pins when the links are in straight alignment with each other, the open end of the saddles flaring, as at 18, so as to guide the pins into seating position, if necessary, irrespective of any wear and consequent relative looseness at the link pins 5.

The above pin and saddle arrangement requires that each pin and the saddle adjacent thereto shall be on the same circle whose center is the center of the adjacent link pin boss, as clearly shown in Figs. 1 and 2.

The supporting structure about which the endless track linkage extends comprises pairs of sprocket wheels 19 spaced to engage the bosses 4. Each wheel has an uneven number of teeth 20, forming boss-engaging sockets therebetween and spaced one-half the distance between adjacent link pins 5. This arrangement provides for successive alternate engagement of the teeth with the bosses so that the wear will be distributed gradually over all the teeth and longer life is assured. The sprocket wheels are mounted in

suitable longitudinal frames 21 disposed between the pairs of wheels, and track engaging rollers 22 are turnably mounted between the frames adjacent each pair of sprocket wheels on centers spaced from the wheel centers a distance equal to the length of a link between its pin centers. These rollers assure of straight line movement of the linkage between the end sprockets, or so that the link pins lie in a line projected between and tangent to the pitch diameter of the sprocket wheels.

It is to be noted that the diameter of the sprocket wheels and the number of teeth thereon are in such proportion to the pitch length of the links and to the size of rollers 22 that sprockets of fifteen teeth (one-half of which are effective at any one time) will cooperate with linkage of a corresponding pitch length to enable a single roller 22 to contact both track surfaces of upper and lower links of the endless track.

It will also be noted that in Fig. 1 I have shown an odd number of links in the endless track, together with sprockets having an odd number of teeth, in order to show the relative positions of the links in the various positions they would successively occupy when in motion.

In the structure shown in Fig. 5, the general arrangement and construction of the links, and the locking or trussing action, is the same as above described. However, the sprocket wheels 19a, instead of engaging the pin bosses 4a of the links L, here engage pins 23 projecting laterally from the link webbing 6a centrally between the end bosses and inwardly thereof. This arrangement permits of a much smaller sprocket wheel than is otherwise the case. In order to prevent possible rocking of the links about the pins 23, when fully engaged with and passing about the sprocket wheels, the shoulders 11a of the tracks 9a form stops then engaging the relatively narrow portions of adjacent links, as shown.

From the foregoing description it will be readily seen that I have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

I claim:

1. An endless track structure including end sprockets, an endless track unit extending about and between the sprockets and comprising a plurality of links of equal length and pivot pins connecting the links at adjacent ends; and idler

rollers adjacent the sprockets mounted on the structure and engaging the links of the lower run of the unit when said lower run is tangent to the sprockets; the horizontal distance between the axis of each roller and that of the adjacent sprocket being equal to the length of a link.

5 2. An endless track structure including end sprockets, an endless track unit extending about and between the sprockets and comprising a plurality of links of equal length with pivot pins connecting the links at adjacent ends; and idler rollers mounted on the structure and simultaneously engaging the inner faces of the links of both the upper and lower runs of the unit; the size of the sprockets relative to the pitch length of a link being such that the horizontal distance between the axis of each roller and that of the adjacent sprocket will be equal to the length of a link, without the periphery of the roller intersecting the axis of the sprocket.

15 3. An endless track structure including end sprockets, an endless track unit extending about and between the sprockets and comprising a plurality of links of equal length and pivot pins connecting the links at adjacent ends; and idler rollers adjacent the sprockets mounted on the structure and simultaneously engaging the links of both runs of the unit when said both runs are tangent to the sprockets; the horizontal distance between the axis of each roller and that of the adjacent sprocket being equal to the length of a link.

20 4. In the combination of an endless trussed-track structure having end sprockets and an endless track passing thereabout and comprising links of equal length pivoted together and having cooperating means to prevent upward flexing of the ground engaging portion of the track, idler rollers adjacent the sprockets mounted on the structure and engaging the links of the lower run of the unit when said lower run is tangent to the sprockets; the horizontal distance between the axis of each roller and that of the adjacent sprocket being equal to the length of a link.
